UNITED STATES PATENT OFFICE.

JOHN J. TOOMEY, OF CHICAGO, ILLINOIS.

RANGE.

Application filed January 10, 1922. Serial No. 528,150.

To all whom it may concern:

Be it known that I, JOHN J. TOOMEY, a citizen of the United States, residing at Chicago, in the county of Cook, State of Illinois, having invented certain new and useful Improvements in Ranges, do hereby declare that the following is a full, clear, and exact description of the same.

My invention relates in general to cooking stoves or ranges such as are used for domestic purposes, and particularly to stoves of this character constructed and arranged for burning both solid and fluid fuels. In ranges of the duplex-fuel type it is customary to locate the fire-box for the coal or other solid fuel at one end of the range at one side of the oven and to pass the heated products of combustion through suitable flue-space leading from the fire-box across the top of the oven, then down along its opposite side and then beneath its bottom, and connected to the chimney-flue by a smoke-pipe. The cooking-top for coal-heat is restricted to the top of the fire-box and the upper coal-heated flue-space. In order to afford standard cooking capacity for every day family use the cooking-top in a coal-range requires four coal-heated openings, and in a gas-range four gas burners, and sometimes five as when a simmering burner is desired. In some duplex fuel ranges having separate coal-heated and gas-heated ovens the latter oven is located above the top of the range at the end opposite the fire-box, and the gas-cooking top is sometimes placed over the coal-cooking top and is raised out of the way when the latter is in use, with the result that the heavy gas-burner top must be manually shifted and the two sets of top-cooking units cannot be used simultaneously. In some duplex fuel ranges either the gas-cooking top is placed at the end of the range opposite the fire-box and beyond the coal-cooking top, or some of the latter's customary four coal-heated openings are omitted to make room for the standard equipment of gas-cooking burners; in the first case the cooking-top is inconveniently long and the gas-burner top frequently extends beyond the end of the range, and in the second the range does not have a standard coal-cooking top. In another type, illustrated for example by the patent to Coulston No. 1,032,816, dated July 16, 1912, the stove top above the usual top-

flue for the products of solid-fuel combustion is provided with two coal-heated openings closed by the usual lids and also with a pair of elliptical openings extending lengthwise of the stove, one on each side of the 60 coal-heated openings, and elliptical casings are located in the top-flue below the elliptical openings to form gas-burner chambers in which gas burners are located in pairs, and these elliptical openings are covered by 65 elliptical plates; as the gas-burner chambers are located in the top-flue these elliptical cover-plates are provided with inlet ports to supply combustion air to the gas-burners and also with cooking-openings above the 70 gas burners closed by removable lids when the burners are not in use, and the elliptical casings are provided at each end with outlet ports for the products of gas combustion leading into the top-flue and controlled by 75 dampers or registers located in these burner-chambers and accessible by removing the lids; the supply pipes for the gas-burners extend out through their casings into the flue space for the coal-combustion products and thence out through a side wall of the stove to gas-valves located at one side thereof, and so the burners cannot be removed for cleaning purposes without taking down the stove construction and disassembling the burner 80 and its pipe, the burner-pipes are subjected to the action of the coal-combustion products passing through the flue space, and the organization requires side-control of the gas-burner valves; also, the gas-burner 85 chambers located in the top flue must be of special form and location in order to avoid eddies and obstructions to the draft through the top-flue, and when the gas-burners are used their lids must be removed and the 90 dampers of the outlet ports in the elliptical chambers must be manually opened, and when the gas burners are not used these dampers must be closed and the lids replaced, so that more or less moving and 95 changing of parts is needed to transform the cooking-top from a solid-fuel burner to a gas-fuel burner or vice versa, and while the solid-fuel may be utilized for culinary purposes or in place thereof the gas burners 100 may be brought into use both forms of heat or fuel cannot be simultaneously used for top-cooking purposes.

The primary objects of my invention are

to provide an improved complete duplex-fuel cooking-top of standard capacity for each kind of heat or fuel comprising four coal-cooking openings and four separate top-cooking heaters within the area of the fire-box and a standard four-burner top, and in which the two kinds of top-cooking units may be used jointly or separately for top-cooking purposes, and in which no parts of the cooking-top need be moved or shifted when it is desired to change from one fuel to the other for cooking at the cooking-top, and also to provide a stove comprising a complete coal-range of standard capacity and a box-cabinet gas-range having a gas-baking oven, a gas-broiling oven and a standard capacity gas-burner top, and in which all the gas burners are controlled from a gas-manifold at the front of the stove.

Other objects and advantages of the invention will be apparent from the disclosure.

The invention consists in the novel and useful constructions and arrangements of parts herein described and then pointed out in the appended claims.

In the accompanying drawings, which illustrate practical embodiments of the various features of my invention and in which the same reference numerals indicate similar parts in the different figures,

Fig. 1 is a perspective view of a range equipped with my invention, portions of the coal-section being broken away to expose internal parts;

Fig. 2 is a longitudinal sectional view on the line 2—2 in Fig. 1;

Fig. 3 is a detail cross-sectional view on the line 3—3 in Fig. 1 showing the intake-end of the top-flue with parts of the wall of the fire-box broken away;

Fig. 4 is a detail cross sectional view on the line 4—4 in Fig. 1;

Fig. 5 is a detail top plan view with some parts broken away and the lid of the cross-channel removed;

Fig. 6 is a detail sectional view on the line 6—6 in Fig. 3, and

Fig. 7 is a view in front elevation of the clean-out piece.

While for the purposes of illustrating all the features of my invention the range shown is in its general design typical of those having separate solid-fuel and gas-heated ovens as above described, it will be understood that my improved cooking-top is applicable to other types of duplex fuel ranges, and it is not necessary to describe in detail the construction of the usual parts of the range shown. In the exemplification shown the coal-section of the range designated in its general parts by the numeral 1 is provided with a fire-box 2 located at one end and at one side of the coal-heated oven 3 and having its top 4 provided with the

usual coal-cooking openings closed by the removable lids 5; and the front-plate of the coal-section is a single casting provided with the usual oven and ash-pit doors. A cooking-top plate 6 extends from the fire-box to the other end of the coal-oven and is spaced above the full length and depth of the oven-top 7 to form the top-flue space 8 for the hot products of coal-combustion. This flue space communicates at one end with the fire-box and at its other end with the down-flue 9 at the side of the oven opposite the fire-box, the products of coal-combustion passing thence through a lower flue 10 beneath the oven and into the usual vertical back-flue 11 connected by a pipe to the chimney. The usual damper 12 is located between the fire-box 2 and its branch 13 of the back-flue so that the necessary straight draft through the fire-box may be provided when starting a solid-fuel fire, this damper being closed from the outside when the fire is brought to the desired intensity so that its hot products of combustion will then pass through the flue space about the oven.

The top-plate 6 is preferably a single casting and comprises parallel horizontal front and rear shelves 14 and 15, respectively, arranged in the same plane and spaced apart along the length of the oven, longitudinal upright front and rear walls 16 and 17 located at the inner edges of the shelves 14 and 15 respectively and inclined from bottom to top slightly toward the center of the plate, upright cross-walls 18 and 19, respectively, spaced apart and extending across the space between the intermediate walls 16 and 17 at approximately the center of the latter and downwardly into their upper portions to form a shallow cross-channel, and the bottom 20 of this channel. The shelves 14 and 15 are suitably spaced above the oven-top 7 to make the flue space 8 of standard height; in the form shown the shelf 14 is provided at its outer edge with a depending flange 21 which is fastened by bolts passing through it and the upturned edge of the oven-top into the upper edge of the front-plate of the coal-stove 1, and the shelf 15 is fastened at its outer edge to a ledge 22 extending above the rear end of the top wall of the oven 3. These shelves are also spaced apart sufficiently so that the space between the upper edges of the walls 16 and 17 at each side of the cross-channel will accommodate a rectangular coal-cooking top-plate 23, and the walls are provided near their upper edges with seating lugs 24 arranged in opposite pairs to which these plates are attached by stove-bolts, each plate having its coal-cooking opening closed by a removable lid 25. The top-flue above the oven thus comprises the lower flue-space 8 under the shelves 14 and 15 of the usual height of the customary top-flue, and the

upper flue space provided by the longitudinal conduit or passage formed between the walls 16 and 17, this conduit in practice being about five inches deep, eleven inches wide at the bottom and seven inches wide at the top. A removable lid 26 covers the cross-channel formed in the top of the conduit, and vertical baffle-plates 27 and 28 are mounted at the front ends of the shelves 14 and 15, respectively, adjacent the fire-box, and extend across the shelves and upwardly to bring their upper ends flush with the upper edges of the walls 16 and 17, respectively, where they are provided with lateral flanges 29 and 30, respectively, upon which the top-plate 4 of the fire-box is fastened. The baffle-plates form upward extensions of the oven-side of the fire-box and have tight joints with the shelves and walls to prevent the products of coal-combustion from passing into the spaces of the cooking-top above the shelves. The upper portions of the front ends of the walls 16 and 17 where these baffle-plates are located are extended outwardly to provide lips 31 projecting beyond the plates into the fire-box as shown in Fig. 2 and flush with the flanges 29 and 30 to provide seats between the lips and the overhanging edge of the inner plate 23 for the inner edge of the fire-box top 4; the outer edges of this top and the outer edge of the rear plate 23 are seated on inwardly extending depressed flanges of the top-frame 32 of the cooking-top. The opposite or rear ends of the walls 16 and 17 are provided with horizontal flanges 33 to which the rear closure-plate 34 of the top-plate 6 is secured. The plate 34 extends across the full width of the top-plate and forms the upper wall of the down-flue 9, its upper edge making a tight joint with the frame 32 and its lower edge being secured to vertical flanges 35 on the corresponding ends of the shelves 14 and 15; the upper end of the outer wall 36 of the down-flue 9 is also secured to these flanges 35 in position to overlap the lower edge of the plate 34. The central part or body of the plate 34 spans the rear end of the conduit forming the upper portion of the top-flue, and its lateral portions or wings form rear baffles to close the openings that otherwise would lead into the down-flue 9 at the rear ends of the spaces above the shelves 14 and 15. The front shelf 14 also has at its rear end a front vertical flange 37 to which is secured the upper end of the vertical portion of the front-plate of the coal-section that forms the front wall of the down-flue 9. The plate 34 and the ends of the walls 16 and 17 are shouldered as shown in Fig. 2 to accommodate the gas-oven structure 38 which is somewhat wider at its upper roaster-portion than at its lower broiler-portion and is mounted on the stove-frame at the end opposite the fire-box. The coal-section of the range is provided at the rear corners of the top-frame 32 with upright brackets, and at its rear with the upright splasher 39 and the top-shelf flush with the top of the oven-casing 38. The rear shelf 15 is extended rearwardly, preferably by a horizontal plate 40 suitably fastened to the frame 1, so that the open spaces at the opposite sides of the conduit will be substantially equal in width. The front space above the shelf 14 is open at its front to the outside air, and the rear space above the shelf 15 and its extension 40 is open at its front to the outside air as the bottom of the splasher 39 either terminates at the top-frame 32 or is provided with a plurality of perforations if it extends down to the plate 40. These open spaces formed immediately under the top-frame 32 by the shelves 14 and 15 with their end baffles and by the vertical walls of the conduit form front and rear burner-boxes on opposite sides of the conduit that are at all times closed to the products of coal-combustion but are open at their fronts to the outside air, so that gas burners located therein will always have an unrestricted and ample supply of combustion air, and will be at all times accessible.

In practice I prefer to close the ends of the flue space 8 under the shelves 14 and 15 adjacent the fire-box to prevent the solid fuel from going into the top-flue; the hot products of combustion from the fire-box will then enter the top-flue through an inlet formed by the opening between the walls 16 and 17 below the front plate 23. For this purpose I extend the lining 41 of the fire-box at the side adjacent the top-flue upwardly and flare its top edge outwardly to overlap the front ends of the shelves and make a tight joint with the lower edges of the baffles 27 and 28, the front edge of the lining making a tight closure with a vertical flange 42 on the outer edge of the baffle 27. As the conduit of the top-flue is flared laterally toward its bottom its intake end extends toward the front and rear ends of the fire-box as shown in Fig. 3 to facilitate the entrance into the top-flue of a sufficient volume of the hot products of coal-combustion to circulate over the entire top of the oven, and the conduit concentrates their upper portion at its top where the coal-cooking openings of the plates 23 are located. Also, by this arrangement I am able to conveniently provide a central clean-out for the top-flue at its inlet. For this purpose the upper edge of the lining is provided with a lip 43 extending into the inlet between the walls 16 and 17, slightly above the oven-top 7, and a clean-out piece 44 is secured on the oven-top and has an inclined skirt or face 45 extending upwardly from the oven-top and making a flush joint with the top of the lip 43; the piece 44 is provided with

4
a depressed flange 46 on its outer edge to underlie the lip and close the joint therewith (Fig. 2). This clean-out piece has opposite lateral arms 47 and 48 at its lower portion located between the oven-top and the flanges 14 and 15, and upon which supporting lips 49 of the lining 41 rest, and the arms are provided with upright webs 50 against which these lips abut. The clean-out piece affords a support for the lining and convenient means by which dirt and soot lodged in the top-flue may be brushed or wiped out into the fire-box.

By the organization above described the 15 coal-cooking top is T-shape in plan, comprising the upper walls of the fire-box and conduit, each of these walls providing ample space for two standard coal-cooking openings as above described so that the coal-cooking top affords the standard top-cooking capacity of the commercial coal-range; and the conduit forming the upper portion of the top-flue is disposed longitudinally in the median line of the cooking-top and 20 leaves ample open space at each of its sides to arrange within the open top the necessary number of additional cooking heaters or units required to give standard top-cooking capacity within the area of the top. 25 While these supplemental cooking units may be of any suitable character, such for example as electric-heaters, I prefer to use gas burners for this purpose.

In practice I arrange these gas burners 30 in tandem pairs in the open burner-boxes on opposite sides of the conduit of the top-flue. In the front burner-box a giant burner 51 and a regulation burner 52 are arranged in line adjacent and parallel with the front wall 16 of the conduit, and in the 35 rear burner-box a pair of regulation burners 53 is similarly arranged adjacent the rear wall 17 of the conduit. If desired a simmering burner may be placed in either 40 burner-box. The conduit and burner-boxes are of sufficient height so that the tops of 45 the burners are slightly below the level of the frame 32 and the top of the conduit, and the parts around the tops of the boxes are 50 provided with inwardly extending depressed flanges 54 to seat the usual removable cooking-top plates 55 that support the cooking-vessels, such as the gratings or grids, flush therewith and above the burners; it will be 55 understood that the usual grids are used when artificial gas is employed, and that the usual top-plates are used when natural 60 gas is employed. By the arrangement of parts described in either case the burner-boxes are always open to the outside air, and the circulation of combustion air is facilitated by the cross-channel which provides 65 an air passage between the burner-boxes, while the gas cooking-top affords the standard top-cooking capacity of the commercial

gas-range. The supply pipes 56 and 57 of the front and rear burners respectively communicate with the burner-box manifold 58 to which the gas is supplied, and which is at the front of the cooking-top and is provided 70 with the usual valves 59 to admit the gas to the air and gas mixers of these pipes, the burners being of the usual blue-flame type and made in integral formation with their supply pipes so that each unit may be removed and replaced, the mixers at the free 75 ends of the supply pipes being arranged to telescope with the jets of the gas-valves in the usual manner for their easy assemblage and disassemblage. The burners are supported in place in horizontal alinement with their valves, preferably by brackets 60 mounted on the outer faces of the walls 16 and 17 in position to aline the burner units horizontally with the gas-manifold 58, 80 and the pipes 57 of the rear burners 53 are supported on the bottom 20 of the cross-channel in the top of the conduit which is in alinement with the brackets so that all the supply pipes are horizontal and in alinement 85 with their valves to provide a straight passage for the fuel from the manifold to the burners. In order to allow the rear units, composed of the pipes 57 and their burners, to be easily removed and replaced 90 the lid 26 of the cross-channel is removable; by lifting this lid and the rear plates 55 the rear burners 53 and pipes 57 may be removed and replaced, as is frequently necessary 95 for cleaning purposes. The front 100 burner units are removable after lifting the front plates 55. Suitable removable drip trays or pans 61 and 62 are located in the front and rear burner-boxes, respectively, below the gas-burners, and may be removed 105 for cleaning purposes.

The gas-manifold or supply pipe 58 extends along the front of the range to supply fuel also to the usual oven-burner (not shown) which in the type of range shown 110 provides heat for the gas-baking oven 63 and the gas-broiling or roasting oven 64 located in the gas-oven structure 38 respectively above and below the gas-manifold at the end of the range opposite the fire-box, the valve 65 for this oven-burner being in front with the valves for the open-top burners, so that the gas-oven burners and cooking-top burners with their valves are at 115 the same level or height to avoid the necessity of the operator stooping down to reach the oven-burner as in a combination oven or of reaching up as in an upper or top oven, or of reaching around to the side of the stove as in the case of a side-control of the 120 burners. The heating elements or units for the compartments 63 and 64 may be electric 125 heaters if desired.

All parts of the coal-cooking top and of the gas-cooking top, constituting a complete 130

cooking-top of standard capacity for each kind of fuel or heat, are organized in the open top above the usual top-flue; no part need be moved when it is desired to change 5 from one fuel to another, and both forms of top-cooking units may be used at the same time on the cooking-top. The gas-burners of the cooking-top are not located in the coal-flue but operate in the open air, 10 and the burners and their supply pipes are protected at all times from the flame and products of the solid-fuel combustion and are easily removed for cleaning by merely lifting their plates and the lid of the cross- 15 channel without shifting or disturbing any other part. Also, I provide a unitary box-cabinet gas-range including a gas-baking oven, a gas-broiling oven, a standard capacity gas-cooking top and a complete coal- 20 range having a coal-heated oven and a standard capacity coal-cooking top, and in which all the gas burners are controlled from a gas-manifold at the front of the stove.

25 This application is a continuation in part of my co-pending application filed April 25, 1921, and bearing Serial Number 434,232.

I claim:

1. A duplex-fuel range provided with an 30 oven, an open-top, a fire-box at one side of the open-top, and having flue-space about the oven including a top-flue opening at one end into the fire-box and having an upper conduit extending along the central portion 35 of the open-top to leave an open space at each of its sides on said top, the fire-box and conduit having a plurality of coal-cooking openings, and top-cooking heaters arranged in the open spaces on the open-top on each 40 side of the conduit.

2. A duplex-fuel range provided with an oven, an open-top, a fire-box at one side of the open-top, and having flue-space about the oven including a top-flue formed with 45 an upper conduit having a laterally flaring intake opening into the fire-box and extending along the central portion of the open-top to leave an open space on each of its sides on the open-top, the fire-box and 50 conduit having four coal-cooking openings, and a gas-cooking top comprising a pair of burners arranged in the open spaces on the open-top on each side of the conduit.

3. A duplex-fuel range provided with an 55 oven, an open-top and a fire-box at one side of the open-top, a top-flue having an upper conduit opening at one end into the fire-box and extending along the central portion of the open-top, the fire-box and conduit each 60 having two coal-cooking openings, a cross-channel in the top of the conduit between its coal-cooking openings, and a front and rear pair of gas-burners arranged on the open-top on opposite sides of the conduit 65 and having supply pipes, the pipes for the

rear burners being removably seated in the cross-channel.

4. A duplex-fuel range provided with an open-top, a fire-box at one side, a top-flue formed with an upper conduit extending 70 along the central portion of the open-top and having its central portion formed with a cross-channel, a top for the fire-box and conduit having coal-cooking openings, a removable lid for the channel in the conduit, 75 and a front and rear pair of gas-burners arranged in the open spaces on opposite sides of the conduit and having supply pipes, the pipes for the rear burners lying in the channel in the conduit below its lid. 80

5. A duplex-fuel range provided with an open-top, a fire-box at one end of the top and a gas-heated oven at its other end, an oven below the top and having flue-space including a top conduit opening into the fire- 85 box and extending along the central portion of the open-top to leave an open space on each of its sides on said top, the fire-box and top-flue having four coal-cooking openings, a gas-cooking top comprising a pair of 90 burners arranged in the open space on the open-top on each side of the conduit, a gas-burner for said gas-heated oven, and a front supply-pipe for all the burners.

6. A cooking range provided with an 95 oven and flue space at one side of the oven, a fire-box having a plurality of cooking-openings at the other side of the oven, a duplex-fuel top located above the oven comprising a conduit extending longitudinally 100 of its central portion and opening at its ends into the fire-box and side-flue and having a plurality of cooking-openings, and an open-front burner-box on each side of the conduit, gas burners in each box, a gas-manifold 105 extending along the front of the top, and supply pipes from the manifold to all the burners.

7. A cooking range provided with an oven and flue space at one side of the oven, 110 a fire-box having a plurality of cooking-openings at the other side of the oven, a duplex-fuel top located above the oven comprising a conduit extending longitudinally of its central portion and opening at its ends 115 into the fire-box and side-flue and having a plurality of cooking-openings and a cross-channel between the cooking-openings, an open-front burner-box on each side of the conduit, gas burners in each box, a gas-manifold 120 extending along the front of the top in alinement with the cross-channel, and supply pipes from the manifold to the burners, the pipes for the rear-burners being supported by the cross-channel in alinement 125 with the manifold.

8. A cooking range provided with an oven and flue space at one side of the oven, a fire-box having a plurality of cooking-openings at the other side of the oven, and a 130

- duplex-fuel top located above the oven comprising front and rear open-front burner-boxes and an intermediate conduit opening at its ends into the fire-box and side-flue and having a plurality of cooking-openings and a cross-channel between the cooking-openings, brackets on the conduit in each burner-box, gas burners removably supported by the brackets, a gas-manifold extending along the front of the top, and supply pipes from the manifold to the burners, the pipes for the rear burners being supported by the cross-channel in horizontal alinement with the manifold.
- 10 15. A duplex-fuel range provided with an oven and flue space at one side of the oven, a fire-box at the other side of the oven, a top-plate comprising front and rear shelves above the oven and an upper conduit opening at one end into the fire-box and at its other into the side-flue, the fire-box and conduit having a plurality of coal-cooking openings, and top-cooking heaters in the open spaces above the shelves of the top-plate on each side of the conduit.
- 20 25. 10. A duplex-fuel range provided with an oven and flue space at one side of the oven, a fire-box at the other side of the oven, a top-plate comprising front and rear shelves above the oven and an upper conduit opening at its ends into the fire-box and side-flue, the fire-box and conduit having four coal-cooking openings, baffle-plates at the ends of the shelves, and a pair of gas burners arranged in the open space above each shelf on each side of the conduit.
- 30 35. 11. A duplex-fuel range provided with an oven and flue space at one side of the oven, a fire-box at the other side of the oven having coal-cooking openings, a top-plate comprising front and rear shelves spaced apart above the oven and upright walls on the inner edges of the shelves terminating at one end at the fire-box and at the other end at the side-flue, plates supported on the walls and having coal-cooking openings, a cross-channel in the top of the walls between the coal-cooking plates, a front and rear pair of gas-burners removably supported on the top-plate and having supply pipes, the pipes for the rear burners being removably seated in the cross-channel, and a gas-manifold on the front of the range.
- 40 45. 12. A duplex-fuel range provided with an oven and flue space at one side of the oven, a fire-box at the other side of the oven, a top-plate comprising front and rear shelves spaced apart above the oven and an intermediate upper conduit having front and rear walls and opening at one end into the fire-box and at its other end into the side-flue, the fire-box and conduit each having

two coal-cooking plates, baffles at the ends of the shelves flush with the top of the conduit, means to close the passages from the 65 fire-box to the spaces between the oven and shelves, a front and rear pair of gas-burners removably supported on the top-plate and having supply pipes, and a gas-manifold on the front of the range.

70 13. A duplex-fuel range provided with an oven, a fire-box at one-side of the oven, and having a flue comprising upper and lower flue space above the oven, means to close the lower flue space from the fire-box, the 75 upper flue space opening at one end into the fire-box, and a clean-out piece on the oven having an inclined face extending from the oven-top into the opening into the fire-box.

80 14. A duplex-fuel range provided with an oven, a fire-box at one side of the oven, a top-plate comprising front and rear shelves spaced above the oven and an intermediate upper conduit opening at one end into the 85 fire-box, a closure for the spaces under the shelves having a lip extending into the conduit, and a clean-out piece on the oven having an inclined face extending from the oven-top to the lip.

90 15. A duplex-fuel range provided with a coal-heated oven, a fire-box at one end of the oven and a gas-heated oven at its other end, and having flue-space including an upper conduit opening into the fire-box and extending along the central portion of the coal-oven, an open-front burner-box on each side of the conduit, the fire-box and conduit having four coal-cooking openings, a pair of gas burners arranged in each burner-box 100 below the top of the conduit, a gas burner for said gas-heated oven, and a front supply-pipe for the gas burners at the level of the front burner-box.

105 16. A duplex-fuel range provided with a coal-heated oven and flue-space at one side of said oven, a fire-box at the other side of said oven, a top-plate comprising front and rear shelves spaced apart above said oven and an upper conduit having upright walls 110 terminating at their front ends at the fire-box and at their rear ends above the side-flue, a plate closing the top of the side-flue and the rear of the conduit, the closure-plate and rear ends of the walls being shouledered, a gas-heated oven on the closure-plate, gas-burners on the top-plate on each side of the conduit and in the gas-heated oven, and a front gas-manifold for the burners.

115 120 In testimony whereof I affix my signature.

JOHN J. TOOMEY.
